INVENTOR.

Geo. B. Owen

Des. 1664

George B. Owen, of New York, N.Y.
Letters Patent No 1664, dated Oct. 21, 1862.

The schedule referred to in these Letters Patent and making part of the same.

To all whom it may concern:

Be it known that I, George B. Owen, of the City, County and State of New York, have invented or produced a new and original design for a Clock Base; and I do hereby declare that the following is a full, clear and exact description of the same, reference being had to the accompanying drawings making a part of this specification, in which

Figure 1 is a face view or front elevation of a clock case constructed according to my design.

Figure 2. a side view of the same.

Similar letters of reference indicate corresponding parts in the two Figures.

This design is intended for small or portable clocks, for mantles and like purposes, and consists first of a base A, having four sides with oblique corners a, in front, which may be described as being plane surfaces formed by the removal of the angles at the front side of the base. The front side of the base is provided with a recess b, having its upper and lower edges parallel with each other and its ends provided with scolloped corners c, as shown in Figure 1. The bottom of this recess is corrugated or made rough, as represented by the dark shade d, in Figure 1, so as to form a contrast with the smooth exterior of the prominent portions of the case.

The body B, of the case rests on the base A, and like the base A, is of quadrilateral form, its front corners formed of oblique plane surfaces e, e, which project a little out from the front side f, of the body of the case.

The body B, does not extend out to the edges of the base a space being allowed to receive a moulding g, all around, of the inverted ovolò form.

The front side f, of the body B, of the case has four recesses h, made in it which are disposed around the dial opening c, the inner sides of said recesses, which are opposite the opening c, being curved corresponding to the curvature of said opening, as shown in Figure 1. These recesses h, like that b, of the base are corrugated or made rough at their bottoms, and between the two lower recesses h, there is a diamond

Des. 16604

shaped projection *i*. There is a diamond shaped projection *j*, also on each plane surface *e. e.* at the front corners of the body *B*. The projections *j* are nearly equal in length to the surfaces *e.* and each has a diamond shaped recess *k*, with a corrugated or rough bottom.

The body *B*, of the clock case is provided with a cap *D*, which is formed of an ovolo *l*, having a torus *m*, above it which is surmounted by a fillet *n*, the cap corresponding in form to that of the body *B*, of the case, and base *A*.

Having thus described my invention what I claim as new and desire to secure by Letters Patent is.

The general configuration of the parts as herein shown and described to form a new and original design for a clock case.

Witnesses.

R. Gawley.

J. W. Combs.
